(57) **CLAIM**

The ornamental design for a connector, as shown and described.

DESCRIPTION

FIG. 1 is a front top perspective view of a connector showing our new design;

FIG. 2 is a front bottom perspective view thereof;

FIG. 3 is a rear perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof;

FIG. 9 is a bottom view thereof;

FIG. 10 is a front top perspective view of an alternate embodiment of a connector showing our new design;

FIG. 11 is a front bottom perspective view thereof;

FIG. 12 is a rear perspective view thereof;

FIG. 13 is a front view thereof;

FIG. 14 is a rear view thereof;

FIG. 15 is a right side view thereof;

FIG. 16 is a left side view thereof;

FIG. 17 is a top view thereof;

FIG. 18 is a bottom view thereof;

FIG. 19 is a front top perspective view of an alternate embodiment of a connector showing our new design;

FIG. 20 is a front bottom perspective view thereof;

FIG. 21 is a rear perspective view thereof;

FIG. 22 is a front view thereof;

FIG. 23 is a rear view thereof;

FIG. 24 is a right side view thereof;

FIG. 25 is a left side view thereof;

FIG. 26 is a top view thereof; and,

FIG. 27 is a bottom view thereof.

The broken lines immediately adjacent to the shaded areas represent the bounds of the claimed design and form no part

(Continued)

thereof. The broken lines depicting the remainder of the connector show features that form no part of the claimed design.
